FURNACE

Filed May 3, 1924

Patented May 24, 1927.

UNITED STATES PATENT OFFICE.

WALTER J. PEES, OF MEADVILLE, PENNSYLVANIA.

FURNACE.

Application filed May 3, 1924. Serial No. 710,784.

The present invention relates broadly to stoves and furnaces, and more particularly to furnaces of the hot air type, although the utility of the invention is not limited in this respect.

At the present time it is customary to construct furnaces of the general character to which the present invention relates, from a series of separate pieces adapted to be joined together, the joints commonly being sealed by a suitable cement. It sometimes happens that during the installation of such a furnace, or during the operation thereof, by reason of an explosion or otherwise, the joints are broken and the parts pushed out of alignment. The present invention contemplates means adapted to be applied to furnaces of this general construction for reinforcing the joints between the respective parts and resiliently holding such parts in position.

In the accompanying drawings there is shown, for purposes of illustration only, one embodiment of the present invention, it being understood that the drawings do not define the limits of the invention as changes in the construction disclosed therein may be made without departing either from the spirit of the invention or scope of my broader claims.

In the drawings:—

Figure 1 is a front elevation of a furnace embodying the present invention, certain of the parts being broken away for sake of clearness,

Figure 2 is a partial transverse sectional view, on a smaller scale, on the line II—II of Figure 1, and

Figure 3 is a perspective view of the door for the fire bowl.

While the present invention is adapted to be applied to furnaces of different types, it is herein illustrated in combination with a hot air furnace of the character embodying an ash pit 2, a fire pot 3, a choke fire bowl 4 and a radiator 5. The various parts of the furnace, which may all be substantially of standard construction, are ordinarily connected by joints 6 which may be sealed by the use of a suitable cement.

In order to provide additional means for tying the sections together to prevent any rupture of the joints either during installation or operation of the furnace, I preferentially provide tie rods 7 suitably located, preferably at substantially opposite sides of the

furnace, although it will be understood that any desired number or arrangement of rods may be employed. These tie rods may conveniently be passed through lugs 8 which are customarily provided on the radiator 5 for cooperation with comparatively short tie bolts 9, and at their lower ends may engage yokes 10. These yokes are preferably of inverted U-shape having out-turned portions 11 adapted to underlie and engage different portions of the base 12 of the furnace. By reason of this construction, the yokes may be easily slipped into position through the desired openings in the base and then turned at substantially right angles to bring the portions 11 into the desired engagement with the base. Thereafter, compression springs 13 may be slipped over the ends of the rods 7, and the springs compressed to the desired degree of initial compression by nuts 14.

In order that the temper of the springs may not be impaired to an extent sufficient to destroy their utility, there are preferably provided heat shields or guards 15 surrounding the rods 7 and abutting at their inner sides against the sides of the ash pit 2 whereby they are effectively held in position. These shields cooperate with the yokes 10 to deflect a large amount of heat from the springs and thereby keep the same as cool as possible.

It frequently happens during the use of furnaces of this general character that by reason of an accumulation of gas there will be a more or less violent explosion. This explosion is frequently responsible for the rupture of the joints 6, as pointed out. It will be apparent that where tie rods 7 are utilized, the rupture of the joints cannot occur so easily and it therefore becomes desirable to provide a catch for the door 16 of such construction that it may readily yield to permit the door to open and thus relieve the pressure within the furnace. This may be accomplished by forming the keeper 17 with a sloping latching surface 18 for cooperation with the latch 19 projecting from the door, and providing sufficient play in the pivots 20 to permit the door to tilt upwardly the required amount to allow passage of the latch over the keeper.

It will be understood that the use of compression springs on the tie rods enables the furnace to expand or contract as is custom-

ary by reason of temperature changes of the different parts thereof. By varying the initial compression on the springs in accordance with the construction of the furnace, it is possible, however, without impairing the ability to expand and contract, to firmly hold the different sections of the furnace in the desired position.

The furnace may be provided with the usual casing 21 through which a portion of the ash pit extends to provide a clean-out opening 22, and with a canopy hood 23 having the sides extending at such an angle that the pipes for the furnace may be installed without the use of sharp elbows.

The advantages of the present invention arise from the provision of a resilient reinforcing means for furnaces, and more particularly from the use of compression springs so mounted that the initial compression thereof may be easily adjusted while at the same time shielding them from the intense heat of the fire pot.

I claim:

1. A furnace comprising a plurality of 25 separable sections including a base and a radiator, a yoke detachably cooperating with the base and whose cross-bar is above the base, a tie rod connected to said radiator and extending through the cross-bar of said 30 yoke, and an adjustable resilient connection between said yoke and said tie rod between the legs of the yoke, substantially as described.

2. In a furnace including a radiator and 35 base, a yoke detachably connected to the base, a tie rod detachably cooperating with the radiator and yoke, a spring carried by said tie rod and forming a resilient connection between said radiator and base, and 40 means for shielding said spring from the heat from the furnace, substantially as described.

In testimony whereof I have hereunto set my hand.

WALTER J. PEES.
